UNITED STATES PATENT OFFICE.

JOHN MILLS, OF WYOMING, NEW JERSEY, ASSIGNOR TO WESTERN ELECTRIC COMPANY, INCORPORATED, OF NEW YORK, N. Y., A CORPORATION OF NEW YORK.

LOADING SYSTEM.

Application filed March 29, 1923. Serial No. 628,507.

To all whom it may concern:

Be it known that I, JOHN MILLS, a citizen of the United States, residing at Wyoming, in the county of Essex, State of New Jersey, have invented certain new and useful Improvements in Loading Systems, of which the following is a full, clear, concise, and exact description.

This invention relates to communication over loaded lines and has for an object to improve the transmission of signals, voice currents in particular, over loaded lines.

The advantages of light loaded telephone lines having a high natural cut off frequency have been pointed out in the application of Carson, Clark and Mills, Serial No. 474,878, filed June 4, 1921. The principal advantages are increased speed of transmission and the reduction of transient effects due to unequal rates of propagation of the various frequencies of importance in speech. The important voice frequencies may be taken to be included in the range from 200 cycles to 2500 cycles, although it is well known that satisfactory speech transmission may be had with a range considerably smaller than this. Frequencies higher than 2500 cycles are present in speech and aid intelligibility if they can be transmitted without distortion. In long lines, however, even if "extra light loaded", the time required for transmission of the higher frequencies may be relatively so great that the resulting distortion or so called transient effects may outweigh the advantages of having these frequencies transmitted.

In accordance with this invention substantially uniform speed of transmission of the important voice frequencies is obtained by using high cut off light-loaded lines and the distorting effect of the higher frequencies is eliminated by preventing them from reaching the receiving station. The cut off frequency of the line should be substantially above the highest frequency to be utilized in speech transmission and with certain lengths of line should be twice as great or more. The upper speech frequencies may be suppressed by any suitable means such as low-pass wave-filters which may be located at repeater stations or at any suitable point or points between a transmitter at one end of the line and a receiver at the other end.

The invention will be more fully understood from the following description and

claims taken in connection with the accompanying drawings in which:

Fig. 1 illustrates graphically a fundamental characteristic of a loaded line, and

Fig. 2 illustrates schematically a portion of a system embodying the invention.

The curve in Fig. 1 shows the relative time of transmission of the various frequencies on a loaded line up to its cut off frequency. The abscissæ are given in terms of the fraction $\frac{f}{f_c}$ in which f represents

frequency as a variable and f_c represents the cut off frequency. The ordinates are given as a function of time according to the fraction $\frac{t-t_0}{t_0}$ in which t represents time as a variable and t_0 represents the time of transmission of zero frequency. The equation of the curve is:

$$\frac{t-t_0}{t_0} = \frac{\sin^{-1} f/f_c}{f/f_c} - 1.$$

It will be seen that over a frequency range from 0 to between 0.6 and 0.7 of the entire range up to the cut off frequency, the difference in retardation only attains about 10%, but for frequencies close to the cut off frequency it increases rapidly and may become as great as 50% or more. In units of time the disparity in time of transmission will of course be greater for long lines than for short lines. Hence, for voice transmission it may be that there will be a net improvement by omitting these higher and much retarded frequency components.

In Fig. 2 is shown a system of the four wire type in which a substation S_A is connected by a two wire line 10 and a balanced transformer 12 to the unidirectional lines 14 and 16. The artificial line N_A performs the usual function of preventing any substantial amount of feed back from line 16 to line 14. A similar arrangement (not shown) terminates the distant end of the four wire circuit.

The line 14 is provided with any desired number of repeaters such as shown at R_1 and R_3 and the line 16 is provided with oppositely directed repeaters R_2 , R_4 etc. The lines 14 and 16 which may be small gauge cable lines are provided with loading coils 20 of such values and spacing that the lines have a high critical or cut off frequency, say

5600 cycles. Reference to Fig. 1 will show that if the critical frequency of the line is 5600 cycles, the time of transmission of frequencies below 2500 cycles will be fairly uniform. Low pass filters indicated at F_1 and F_2 are accordingly provided to suppress the speech frequencies above 2500 cycles or at least to reduce their amplitude at the receiving station to a harmless value.

10 While the invention has been described as applied to a four wire system, it obviously is adapted for use in other types of systems and may be applied thereto in a great variety of manners within the scope of the appended claims.

15 The invention claimed is:

1. A telephone system comprising a loaded line having a critical frequency such that the higher speech frequencies are transmitted substantially slower than the frequencies of principal importance to intelligibility and means for reducing the efficiency of transmission of said higher frequencies.

2. A telephone system comprising a loaded line having a critical frequency such that the higher speech frequencies are transmitted substantially slower than the frequencies of principal importance to intelligibility and means for reducing the efficiency of transmission of said higher frequencies, the range of frequencies having their transmission reduced being at least one third as great as the range of frequencies freely transmitted.

3. A telephone system comprising a loaded line having a critical frequency such that the higher speech frequencies are transmitted substantially slower than the frequencies of principal importance to intelligibility and

a wave filter for attenuating said higher frequencies. 40

4. A telephone system comprising a loaded line having a critical frequency such that the higher speech frequencies are transmitted substantially slower than the frequencies of principal importance to intelligibility and a wave filter for attenuating said higher frequencies, said wave filter having a cut off frequency of the order of one half said critical frequency. 50

5. A telephone system comprising a loaded line having a critical frequency of the order of 6000 cycles and means for substantially suppressing speech currents above a frequency of the order of 2500 cycles. 55

6. A telephone system comprising a loaded line having a critical frequency of the order of 6000 cycles, means for supplying speech currents to said line, and a low pass filter in said system in the path of said speech currents and having a cut off frequency of the order of 2500 cycles. 60

7. A telephone system comprising a loaded line having a critical frequency such that the higher speech frequencies are transmitted substantially slower than the frequencies of principal importance to intelligibility and having a length such that the actual time lag of said higher frequencies is substantial, and a wave filter for attenuating said higher frequencies, said wave filter having a cut off frequency sufficiently lower than said critical frequency to produce a net gain in intelligibility. 70

In witness whereof, I hereunto subscribe my name this 20 day of March, A. D. 1923.

JOHN MILLS.
